UNITED STATES PATENT OFFICE.

GEORGE PENN, OF SYRACUSE, NEW YORK.

DESIGN FOR A WAGON-SPRING.

SPECIFICATION forming part of Design No. 22,632, dated July 18, 1893.

Application filed March 13, 1893. Serial No. 465,829. Term of patent 14 years.

To all whom it may concern:

Be it known that I, GEORGE PENN, a citizen of the United States, residing at Syracuse, county of Onondaga, and State of New York, have invented and produced a new and original Design for Wagon-Springs, of which the following is a description, reference being had to the accompanying drawing, in which I show an isometrical elevation of the wagon-spring complete.

The leading feature of my design comprises a wagon spring concaved in its general appearance, with its ends bent upwardly and curved inwardly, thence downward and then

bent horizontally, as shown. The horizontal table within the C-shaped ends falls within the regular curved contour and thus presents a pleasing effect.

What I claim as my invention, and desire to secure by Letters Patent, is—

The design for a wagon spring, substantially as herein described and shown.

In witness whereof I have hereunto set my hand this 9th day of March, 1893.

GEO. PENN.

In presence of—

HOWARD P. DENISON,
C. B. KINNE.
